UNITED STATES PATENT OFFICE.

HARRY P. PRATT, OF CHICAGO, ILLINOIS, ASSIGNOR, BY MESNE ASSIGNMENTS, TO HIMSELF, CHARLES C. BONNEY, JOHN A. HAMLIN, AND CHARLES E. BARRETT, ALL OF SAME PLACE, AND WILLIAM R. PLUM, OF LOMBARD, ILLINOIS, TRUSTEES.

TELEPHONE.

SPECIFICATION forming part of Letters Patent No. 310,961, dated January 20 1885.

Application filed October 1, 1883. (No model.)

To all whom it may concern:

Be it known that I, HARRY P. PRATT, a citizen of the United States, residing at Chicago, in the county of Cook and State of Illinois, have invented a new and useful Improvement in Telephones, of which the following is a description, reference being had to the accompanying drawings, forming a part of this specification.

10 My invention relates to that class of telephone-instruments known as "receivers," and it consists in the construction and arrangement of parts, which will be hereinafter more fully described, and pointed out in the claims.

15 The object of my invention is to produce an instrument which shall more cheaply, perfectly, clearly, and distinctly reproduce vocal and other sounds and signals than has heretofore been accomplished by other instruments 20 for a like purpose. This result I attain by the use, in a suitable box or case provided with a diaphragm or plate made of iron or other suitable substance, of a coil of wire made without a core, the wire being wound tightly and 25 evenly, each convolution of which is glued or cemented to the other convolutions, so as to present an even or nearly even surface at both top and bottom. This coil I place in a box or case, the ends of the wire being electrically 30 connected in the usual manner, and secure it firmly to the case beneath a diaphragm or plate of iron or other suitable substance. Through this coil I pass a current of electricity, which so acts upon the plate or diaphragm 35 as to cause it to give forth sounds, speech, or telegraphic signals received over the line from the transmitting-instrument in response to the direct action of the electric current, in clear and distinct tones, as uttered or delivered.

40 A core has heretofore been regarded as essential to the successful operation of a coil in a receiving-telephone instrument; but I have discovered that such core may be dispensed with to advantage, and I therefore dispense 45 with the same, and substitute therefor a solenoid or simple coil made without a core in

place of the compound coil and core formerly used.

I am aware that magnets have sometimes been otherwise attached to or connected with 50 the receiving-coil; but I do not use any such magnet in connection with my solenoid.

By my said invention I overcome the confusion of tones found in the use of other instruments, and obtain a clear and satisfactory 55 reproduction of sounds, speech, or signals transmitted from the other end of the line, and cheapen the cost of the instrument. My invention is of especial advantage where underground wires are used.

60 In the accompanying drawings, which form a part of this specification, and in which similar letters of reference refer to like parts, I have shown and illustrated my invention.

Figure 1 represents a cross-sectional view 65 of my telephone, showing one-half of the case cut away, the central coil being represented entire. Fig. 2 is a top view of the same, with the upper casing and ear-piece and top plate removed, so as to expose the central coil. Fig. 70 3 is an elevation of the upper plate, or the one which is placed between the coil and the ear-piece. Fig. 4 shows a modification having two coils instead of one. Fig. 5 also shows a modification, two coils being used the same as 75 in Fig. 4, and the diaphragm being divided into two plates instead of one. Fig. 6 represents my invention as the same may be applied for receiving telegraphic signals.

A represents the outer case of the electro- 80 phone or telephone.

B represents the ear-piece upon one side of said case.

C indicates the coil.

D is the top plate, placed over the coil and 85 under the ear-piece.

E is the lower plate.

F is the surrounding band by which the coil is secured or held in position.

g and h are the binding-posts with which 90 the ends of the wire composing the coil are connected.

H and I indicate the two coils in the modified construction shown in Figs. 4 and 5.

r and p represent the two upper plates used in the modification shown in Fig. 5.

5 The coil C should be wound tightly and evenly, with each convolution glued or cemented, so as to present an even or nearly even surface at both top and bottom. Over the coil C, I place a suitable plate, D, preferably of iron, and in the form shown in Fig. 3. Both of the plates D and E may, however, be made round, square, or of such shape as will answer the desired purpose. I do not confine myself to the use of a single coil, nor of a single plate, nor to the precise construction of coils and plates shown in the drawings, but desire to secure my right to all forms and modifications of the instrument which come within the principle of my invention. For example, 15 I contemplate the use of a secondary plate or diaphragm on the farther side of the solenoid or simple coil, as shown in Fig. 1; and, instead of a single coil such as I have described, two or more may be used in connection and combination with such plate or plates. The shape and thickness of the plates may be varied to suit the size and work of the instrument, all such variations being mechanical details.

20 The modifications shown in Figs. 4 and 5 need but little explanation, and consist in two coils instead of one in the same case, and held in position by surrounding bands, a single plate being used over the same.

25 My telephone may also be attached to a wire over which telegraphic signals are transmitted by the use of an ordinary telegraph-key. The person receiving the communication may, by holding my telephone to the ear, readily read such signals, and in this manner the noise and 30 confusion which exist in all telegraph-offices may be overcome, and an unauthorized person be prevented from securing information, as he can easily do when an ordinary relay and sounder are used. Fig. 6 is designed to 35 show this application of my invention.

40 The plate or diaphragm in my instrument is non-polarized.

45 I use the term "non-polarized" in the application and in the claims to denote the condition of the diaphragm when not in action, and to distinguish my instrument from others

in which the diaphragm is in contact or connection with one or more magnets.

The operation of my instrument will be readily understood by those skilled in the art. 55

Having thus described my invention, what I claim, and desire to secure by Letters Patent, is—

1. In an instrument for receiving sound, speech, or signals, a non-polarized plate or 60 diaphragm made of iron or other suitable substance, in combination with a coil or coils of wire without a core, substantially as described, and for the purpose set forth.

2. In an instrument for receiving sounds, 65 speech, or signals, the combination of the case A, the ear-piece B, the coil C, without a core, and the non-polarized plate D, made of iron or other suitable substance, all arranged, constructed, and operated substantially as de- 70 scribed, and for the purpose set forth.

3. In an instrument for receiving sounds or signals, the combination of the case A, the ear-piece B, the coil C, without a core, the non-polarized plate D, made of iron or other suitable substance, and the plate E, constructed 75 substantially as described, and for the purpose set forth.

4. In a telephone, the combination of the case A, the non-polarized plate D, made of 80 iron or other suitable substance, and one or more coils without a core or cores, substantially as described, and for the purpose specified.

5. In an instrument for receiving sounds, 85 speech, or signals, a coil or coils without a core or cores, in combination with one or more non-polarized plates or diaphragms, made of iron or other suitable substance, placed between said coil or coils and the ear-piece, 90 substantially as described, and for the purpose set forth.

6. In a telephone receiving-instrument, the combination of the case A, ear-piece B, non-polarized diaphragms or plates, coil C, sup- 95 port F, and binding-posts g and h, substantially as described, and for the purpose set forth.

HARRY P. PRATT.
